UNITED STATES PATENT OFFICE.

NELL RILEY SCOTT, OF ALBANY, OREGON.

HOOK-AND-EYE FASTENER.

1,378,286.

Specification of Letters Patent. Patented May 17, 1921.

Application filed June 3, 1920. Serial No. 386,311.

To all whom it may concern:

Be it known that I, NELL RILEY SCOTT, a citizen of the United States, residing at Albany, in the county of Linn and State of Oregon, have invented certain new and useful Improvements in Hook-and-Eye Fasteners, of which the following is a specification, reference being had to the accompanying drawings.

10 This invention relates to garment fasteners or hooks and particularly to a hook used in connecting with an eye to secure opposite parts of a garment to each other.

An object of the invention is to provide a hook of this character including means which permits the hook to be sewed at both end portions to a garment, so as to position the hook permanently at the place desired.

Another object is to provide a hook of this character which is formed from a small length of wire.

A further object is to provide a hook of this character which provides means for fastening the hook end portion to the garment without forming loops or like projections at the bend of the hook.

With these and other objects in view the invention consists in the improved construction and arrangement of parts to be hereininafter more particularly described, fully claimed and illustrated in the accompanying drawings, in which:

Figure 1 is a front elevation of a hook constructed in accordance with an embodiment of the invention;

Fig. 2 is a side elevation;

Fig. 3 is a section taken on the line 3—3 of Fig. 2; and

Fig. 4 is a rear elevation.

Referring to the drawings, 5 designates a length of wire bent at its intermediate portion to provide parallel arms 6 and 7, the bent intermediate portion serving as the bill of the hook. The arms 6 and 7 are bent in spaced relation to the intermediate portion upon themselves to provide arm portions 8 and 9 which extend in spaced parallel relation to the arms 6 and 7.

The end portions of the arms 8 and 9 are extended beyond the bill of the hook, the arm 8 being extended outwardly away from the arm 9, while the end portion 10 of the arm 8 and end portion 11 of the arm 9 are extended in the same direction that is toward one side of the fastener to provide loops 12. These loops are sewed to the gar-

ment and serve to hold the upper portion of the hook in position. The end portion 10 is extended back toward the arm 8 in parallel relation to the arm 8 and the arm 9, and between said arms, the extremity of the end portion 8 being provided with a safety arch 13 which is disposed in parallel relation to the arms 6 and 7 and the hook formed by said arms. By this means the loop or eye that is engaged with the hook is prevented from accidental disengagement by means of the safety arch, it being necessary for the eye or thread loop to ride over the arch in order to become unfastened. The end portion 11 of the arm 9 is extended back toward the arm 9 in parallel relation thereto and is then gradually extended from its parallel position, across the arm 9 and has its end portion positioned upon the arm 9, the extremity 14 of the end portion 11 being disposed in right angular relation to said end portion 11 and laterally of the fastener, closely adjacent the bend of the arms 6 and 7.

It will be noted that the extremity of the end portion 10 terminates in spaced relation to the bend of the hook so that a space is left between the lower portion of the arms 8 and 9 over which the extremity 14 extends. By this means, thread may be engaged with the extremity 14 and thereby cause the extremity to force the end portions of the arms 8 and 9 into engagement with the garment. At the same time, the extremity 14 is concealed by the hook and all projecting loops or the like fastening means at the bend of the hook are eliminated.

It will be noted that there is no waste of material in the formation of this hook as every portion thereof performs an important function. It is not necessary to loop any portion of the device around an adjacent portion which would necessarily consume material. All of the portions of the hook with the exception of the arch 13 and the extremity 14 are disposed either in the same plane with the adjacent part or parts, or in a plane parallel with the adjacent part or parts. In view of this, the eye that is engaged with the hook does not encounter any projections when being applied to the hook, and as the extremity 14 also serves to brace the lower portion or bend of the hook, the danger of the eye distorting the hook portion is eliminated.

Another important feature is that the end

portion 10 of the arm 8 is disposed between the arms 8 and 9 so that the arch 13 will be positioned centrally of the hook. The end portion 11 of the arm 9 is extended in the same direction as the end portion 10 that is toward one side of the fastener and then extended on the outside of the hook so as to cause the extremity 14 to extend laterally of the arms 8 and 9. In view of this, the arm 9 is disposed between the end portions 10 and 11. By this novel formation, the arch 13 and the extremity 14 of the end portion 11 are positioned at a point where they will accomplish the best results without wasting material, by forming unnecessary loops and bends.

What is claimed is:—

1. A garment fastener formed of one piece of wire and including two inner and two outer parallel bars, loops formed at the junction of the inner bars with the outer bars, one of said outer bars having one of its end portions disposed upon the adjacent inner bar and extending transversely of the remaining bars.

2. A garment fastener formed of one piece of wire and including two inner and two outer parallel bars, loops formed at the junction of the inner bars with the outer bars, the end portion of one of said outer bars adjacent the loops of said bar being parallel to the corresponding portion of the

adjacent inner bar, the remaining portion of said outer bar being gradually extended across said inner bar and having its extremity extended transversely of the remaining bars.

3. A garment fastener formed of a single piece of wire, said wire being bent at its intermediate portion to provide parallel bars, 40 said bars being bent adjacent the first mentioned bent portion back upon themselves to provide a hook, said bars extending beyond the bill of the hook, the end portions of the bars being bent upon themselves in the same 45 direction and in angular relation to the first mentioned bent portion of said bars to provide sewing loops, each of the remaining end portions of the bars being extended in parallel relation to said bars closely adjacent its respective bar, the extremity of one end portion of one of said bars being bent to provide a safety arch, said arch being disposed in spaced relation to the first mentioned bent portion of said bars, the extremity of the other end portion of the other bar being bent in angular relation to said bar closely adjacent the first mentioned bent portion of said bars and laterally thereof to provide a sewing arm.

In testimony whereof I hereunto affix my signature.

NELL RILEY SCOTT.
